MEANS FOR SPOTTING A FLUID IN A WELL

James D. Haynes, Kilgore, Tex., and Orlin W. Lyons, Shreveport, La., assignors to The Dow Chemical Company, Midland, Mich., a corporation of Delaware

Application June 14, 1945, Serial No. 599,450

5 Claims. (Cl. 166—1)

1

The invention relates to delivering a fluid to a selected elevation in a deep well. It more particularly concerns means for delivering a liquid or fluid material to a prearranged elevation or zone in a deep well through a tubing string.

In the construction and operation of deep wells, it is oftentimes desirable or necessary to deliver a charge of fluid material of one kind or another to a specific elevation in a well bore, as for example, that of the producing formation when it is to be treated with an acid solution.

The operation of delivering a liquid or fluid to a specific elevation in a well bore is generally referred to as spotting. Spotting of liquid materials is usually attempted through the tubing and the liquid or fluid involved may be delivered from the tubing into either the uncased or cased well bore, in the latter case usually opposite perforations in the casing.

Several disadvantages inure to such practice among which are that there is no satisfactory way of determining just when the fluid, which is to be delivered from the tubing into the well, begins to emerge from the tubing, when the delivery is complete, and the exact amount of fluid delivered. Without this knowledge, accurate control of the level or elevation of the delivered liquid outside the tubing is difficult, if not impossible, to achieve. A part of the difficulty arises from the nature of the tubing in that its volume is not precisely predictable under the conditions of use due to variations in its distention under pressure, variations in the amount of space at the tubing collars or joints, and various dimensional inaccuracies in the tubing itself. In addition, the volume of fluid retained, if any, in the tubing is not predictable. Another factor militating against accurate spotting, through the tubing, is occasioned by the mixing which inevitably occurs at the interface between the fluid to be spotted and the displacing fluid which follows it. When the volume of fluid to be delivered is relatively small many of these difficulties are accentuated. For example, in the application of resin-forming liquids to sealing and plugging operations in well bores, as described in U. S. Patent 2,274,297, cases arise in which it is highly desirable to deliver a small but precisely known amount of resin-forming liquid at a specific elevation in a well bore, as in sealing a zone of water infiltration adjacent to an oil zone without sealing the latter, plugging back a short section of the well hole, and forming a seal behind the casing through perforations. In carrying out such operations, the success of the work is largely de-

2

termined by the accuracy with which a precisely known volume of cementing liquid can be spotted in the well. In any event, in so far as we are aware, there is no commercially available apparatus for use in overcoming the various difficulties inherent in conventional spotting devices and methods.

The principal object of the invention is to provide an improved means for spotting a fluid in a well. Other objects and advantages will appear as the description proceeds.

In brief, in practicing our invention, the fluid to be spotted is delivered to the prearranged zone in the well bore through a conventional tubing string to which has been fitted one or more special cylindrical constrictional elements of bores which are in axial alignment with that of the tubing string and have a cross-sectional area of at least 20 per cent less than that of the tubing. We employ in conjunction with the foregoing devices one or more highly resilient piston-like plugs having a diameter slightly larger than the bore of the tubing so as to form a fluid seal with the wall of the tube when inserted therein and are able to slide in the bore of the tubing when under moderate differential pressure but can be expelled through the aforesaid constrictions only under differential pressures substantially much greater than that required to bring about their longitudinal movement through any other portion of the apparatus. In some instances, the annular space between the outside of the tubing and the well bore may be packed off either at, above, or below the cylindrical constrictions so as to prevent the fluid material delivered into the well through the tubing rising above a designated elevation. Spotting may be accomplished by positioning the discharge end of the tubing apparatus at the desired elevation in the well; introducing the charge of fluid material to be injected into the well into the tubing string, a piston-like resilient plug having been inserted in the tubing in front of the charge, so that the plug is caused to move down the tubing in piston-like fashion as the charge moves down the tubing; inserting behind the charge a second piston-like resilient plug; and then forcing the charge and the resilient plugs in the proper sequence through the constrictions into the well by the application of fluid pressure behind the last resilient plug. By the foregoing method, thus briefly outlined, complete purging of the tubing string of the fluid to be introduced into the well is obtained, the amount and position of the fluid so delivered to the well is precisely determined

so that spotting is accurately and efficiently accomplished.

The invention is further exemplified in the following description and illustrated in the accompanying drawings, in which—

Fig. 1 illustrates in vertical section the upper portion of a well suitably equipped for carrying out the invention and disclosing a resilient piston plug in position in the lock chamber in readiness to be driven into the well ahead of a fluid material to be spotted.

Fig. 2 illustrates in vertical section the lower portion of the well of Fig. 1 and discloses the combination of a tubing string and cylindrical constrictional element attached thereto; the discharge end being in position for spotting a liquid opposite a specific zone traversed by the wellbore.

Fig. 3 is an enlarged view partly in central vertical section of a form of resilient piston-like plug adapted to make a sliding fit with the bore of the tubing string.

Fig. 4 is a similar view to Fig. 2 and shows a charge of fluid material to be spotted located between two resilient piston-like plugs, the charge having been driven to the bottom of the tubing by a pressuring fluid.

Fig. 5 is a similar view to Fig. 4 and shows a further stage in movement of the resilient plugs and charge of fluid material.

Fig. 6 is a similar view to Fig. 4 and shows the completion of the delivery of fluid material into the well.

Fig. 7 is a similar view to the lower portion of Fig. 2 showing a modification of the apparatus of Fig. 2 and includes a packer on the tubing above the cylindrical constrictional element.

Fig. 8 is a similar view to the lower portion of the well of Fig. 2 and shows a modification of the apparatus of Fig. 2, including a packer below a modified form of a cylindrical constrictional element, the modified element permitting it to function as a back-pressure valve in combination with a resilient piston-like plug shown in position to close the valve.

Fig. 9 illustrates a preferred form of the apparatus and shows in vertical section a pair of cylindrical constrictional elements, the upper one being a back-pressure valve, joined by a tubular section adapted to accommodate resilient piston-like plugs.

Figs. 10 to 14, inclusive, are each similar views in vertical section of a perforated portion of the cemented casing of the well of Fig. 2, the perforations being opposite a zone to be sealed with a fluid agent and shows the sequence of operations of spotting the sealing agent in the zone using the apparatus illustrated in Fig. 9 in combination with a tubing string.

Referring more particularly to the drawings, wherein-like reference numerals designate similar parts in each of the figures, the well in which the apparatus and method may be used may be cased in part, as illustrated, and the bore traverse one or more geological strata or zones, provision being made for suitable accessories attached to the well above ground level for facilitating the practice of the invention, as shown in Fig. 1. In this view, the well bore 1 is drilled into the earth 2 and provided with a casing 3 cemented in place with cement 4. Attached to the top of the casing is a casing head 5 having valved connections 6 and 7, respectively, leading to the interior of the casing. A string of tubing 8 is suspended from the casing head and projects above it, the upper end being valved with the gate valve 9 so as to provide a

clear passage therethrough, when the valve is open, having a diameter at least equal to that of the inside of the tubing. A nipple 10 connects the gate valve to the cross 11 having lateral connections to valves 12 and 13, respectively. A lock chamber comprising a length of tubing 14 is attached to the top opening of the cross in axial alignment with nipple 10 so as to give a continuous unobstructed tubular bore (when valve 10 is open) connecting the lock chamber with the tubing string. The top of the lock chamber is provided with a removable closure plug 15 and lateral pipe connection 16 leading to the valve 17 which in turn is connected to one side of the T 18, the opposite side being connected to the valve 13. The T 18 is provided with the valved connection 19 which may lead to pumps, truck tanks, or like equipment, not shown, for supplying treating fluids, pressuring fluids, cementing materials, etc., as may be required according to the treatment to be made. Pressure gauge 20 communicates with the interior of the lock chamber 14 for registering pressure therein applied to the tubing string.

In the embodiment shown in Figs. 2, 4, 5, and 6, the lower portion of the well bore is cased to the casing seat 21 leaving the uncased portion 22 into which the tubing string 8 extends. To the externally threaded end 23 of the tubing string is screw threaded a tubular section comprising the bore constrictional element 24. This element comprises a tubular body portion 25 having a reduced diameter cylindrical bore 26, its cross-sectional area being between about 25 and 70 per cent less than that of the tubing string. The preferred cross-sectional area is about 60 per cent less than that of the bore of the tubing string. The length of the reduced diameter bore is at least 3 and need not exceed 10 times its diameter. The upper end of the reduced diameter cylindrical bore 26 is enlarged to form the mouth or funnel section 27 with sides sloping at about 60° to the axis of the bore and an internally threaded section 28 adapted to engage the externally threaded end 23 of the tubing string. The funnel shaped section 27 provides a gradual reduction in diameter from that of the bore of the tubing to that of the reduced diameter cylindrical bore 26. The discharge end 29 of the cylindrical bore is shown positioned opposite a zone 30 in which a fluid is to be spotted.

A suitable form of resilient piston-like plug, which is illustrated in Fig. 3, comprises a mass of natural or synthetic rubber, preferably "neoprene," or like resilient or yieldable material in generally cylindrical form; the length being about 3 to 8 or preferably 6 times its diameter. The central portion 33 is preferably solid resilient or yieldable material. The ends are countersunk, thereby providing the recesses 34 and 35 and forming annular lips 36 and 37, respectively. Undercut annular grooves 38 and 39 provide the upwardly directed lip 40 and the downwardly directed lips 41, respectively. The diameter of the plug is substantially the same or preferably slightly larger than the internal diameter of the tubing string in which the plug is to travel so as to make a sliding sealing fit with the tube wall.

The apparatus of Figs. 2, 4, 5, and 6 may be modified by including a packer 42 on the end of the tubing string 8, as shown in Fig. 7, the constrictional element 44 being joined to the packer by the nipple 45 which may be of drillable pipe such as a magnesium or aluminum alloy. In this arrangement, there is a continuous unrestricted

bore from the tubing string through the central bore 46 of the packer to the element 44.

The single constrictional element, shown in Fig. 8, and indicated generally by numeral 47, is similar in construction to the constrictional elements illustrated in the preceding figures in that the cross-sectional area and ratio of length to diameter of its constricted bore 70 are as specified for the previously described bore constrictional element. It has the added features of a recessed lower end comprising an internally threaded portion 48 and a valve seat portion 49. As shown, the valve seat has the form of the lower portion of an inverted cone, the base portion 50 having the same diameter as that of the bore of the tubing string 8 to which the device is attached, and seat portion 49 a slope corresponding to the flared portion 36 of a resilient plug. A satisfactory slope is one making an angle of 45° with the axis of the bore of the constrictional element. The base 50 of the conical portion coincides with the cylindrical ring portion 52. As shown, the constrictional element 47 is arranged below and screw threaded to the tubing string 8 just above and in combination with a packer 53 to which the element is joined by the tubular section 54 having an upper externally threaded end 55 engaging the internally threaded portion 48 and a lower externally threaded end 56 engaging the internally threaded coupling member 57 on the upper end of the packer 53 which may be of any conventional form suitable to seal the annular space in the well. The interior of the packer is provided with a continuous tubular passage 58 having a bore of the same diameter as that of the tubing string. The tubular section 54 is made of sufficient length to accommodate from one to three or four resilient plugs within its bore. A tail pipe 59 is screw threaded to the lower coupling 60.

In Fig. 9, a pair of bore constricting elements, instead of a single constrictional element, is provided, which may be used, in combination with a tubing string. The upper constrictional element 63 is similar to that shown in Fig. 8, its lower end 64 being screw threaded to the upper end 65 of the tubular section 66. This tubular section is made of sufficient length to accommodate at least one or two resilient plugs and is preferably about 4 times the length of a plug. The lower end 67 of the tubular section is screw threaded to the internally threaded upper end 68 of the lower bore constricting element 69, this lower constrictional element being of the same form as that of Fig. 2.

In Figs. 10 to 14, inclusive, a portion of the cemented casing 3 in the well bore is shown having a series of perforations 71 opposite a zone 72 to be treated, the upper portion of the well being equipped as in Fig. 1.

In practicing the method and in operating the various forms of the apparatus disclosed, the well is generally equipped above ground with the lock chamber apparatus shown in Fig. 1, connection being made at 19 for supplying the treating fluid and a pressuring fluid by means of which the treating fluid is to be driven into the well and spotted at a specific elevation as desired. The simple form of spotting device, illustrated in Fig. 2, in position in the well, may be attached to the tubing 8 before lowering it into the wall, the discharge end 29 being positioned at the elevation at which the treating fluid is to be delivered to the uncased portion of the well bore 22. It is usually desirable, if not necessary, to bridge the lower portion of the well hole as by filling the portion to be bridged preferably with a temporary filling

or plugging material to the level above which spotting of a treating fluid is to be achieved so as to exclude the treating fluid from the well bore below the zone to be treated. One way of temporarily bridging the well hole with a filling material so that the bridge may be removed after use is described in a companion application of Philip J. Lehnhard, Jr., Serial No. 594,727, filed May 19, 1945, now abandoned. According to this method, an especially graded granular material, specifically 20-80 mesh sand (referring to standard sieve sizes), is circulated into the well hole through tubing. After the sand has settled into position to form the column 31, the top of it is sealed with a cap 32 of a non-penetrating liquid mixture, such as drilling mud. If desired, other bridges may be used.

After plugging back the well, when necessary, to the desired elevation and positioning the tubing and appended apparatus as in Fig. 2, so that the lower end of the tubing is adjacent the zone to be treated, spotting a fluid agent therein is carried out as follows: A first resilient piston-like plug, such as one of the form illustrated in Fig. 3, is placed with lip 37 downward in the lock chamber 14 opened by removing closure plug 15. During this operation, valves 9 and 19 are closed and 12 opened so that fluid in the chamber, displaced by the plug, can escape from the chamber. After placing in the chamber 14 the first plug so that it occupies a position between the cross 11 and the connection of valve 13, as indicated by 83, valves 12 and 13 are closed, and valves 9, 17, and 19 are opened. The charge of fluid material to be spotted in the well is then introduced into the tubing 8 by pumping it into the lock chamber above the first plug through the valved connection 19. The volume of the charge material to be spotted is determined in advance according to the needs of the well and may be measured accurately before introduction so that the volume delivered to the well may be thus known accurately. The pressure required at the head of the liquid column above the plug, to cause the charge and lower plug to descend in the tubing 8, is observed on the pressure gauge 20. After the charge is introduced gate valves 9 and connection 19 are closed, the closure plug 15 removed, and a second or top resilient plug is inserted in the lock chamber in the same manner as the first plug while allowing the fluid it displaces to be drained from the chamber through valve 12. The closure plug 15 is then replaced and valve 12 closed. Valved connections 13 and 19 and gate valve 9 are opened, thereby making the apparatus ready for driving the liquid charge between their upper and lower subtending plugs into the well.

This is accomplished by introducing a pressuring fluid, such as oil or water, through connection 19 under suitable pressure into the tubing 8, thereby driving the charge 35 and the upper and lower plugs along the tubing 8 until the lower plug reaches the constrictional element 24, as shown in Fig. 4.

During the introduction of driving or pressuring fluid 84, the pressure exerted on it by the pumping means (not shown) is observed on gauge 20, thereby indicating the location of the plugs in the tubing. Normally at first, there is only a small or even a negative driving pressure depending upon the extent to which the hydrostatic head of the entire liquid column in the tubing is counterbalanced by that, if any, outside the tubing and the frictional drag of the plugs, and this pressure may remain relatively low or in-

crease regularly as the plug descends in the tubing string until the first or lower plug proceeds to the point where the lip 37 abuts the funnel section 27, as shown at 83A. It is to be understood that the bore of the tubing string is substantially uniform and unobstructed from end to end so that the resilient plugs may move along the tubing smoothly without significant impedance, the slight retardations met with as the plugs traverse the tubing joints being disregarded. All the usual forms of tubing are satisfactory for the purpose and the undivided sections may be joined in any convenient manner as by threaded collars. When the lower plug thus reaches the constrictional element 24, there is an abrupt rise in pressure which registers on gauge 20 and this rise in pressure indicates that the fluid charge 85 and the lower plug ahead of it is in position to begin its delivery into the well bore 1. The pressure applied to the driving fluid 84 is then increased sufficiently to drive the lower plug from its position at 83A into and through the constricting throat or bore 26. As illustrative of the increased pressure to be surmounted, a resilient plug consisting of a 2-inch diameter grooved cylinder, 6 inches long, of "neoprene" with countersunk ends requires a differential pressure of 1000 to 1800 pounds per square inch for forcing it through a constrictional element having a cylindrical bore 7 inches long and 1.187 inches in diameter. As the lower plug is driven into the constrictional bore, it contracts in diameter and elongates in conformity with the bore 26 and on emerging again expands, as shown in Fig. 5, where the lower half 86 has emerged from the constricted bore while the upper half 87 is shown in the compressed state. On being expelled from the constricted bore 26, the lower plug drops into the well hole as at 83B and the pressure gauge 20 shows a decreased reading corresponding to the decline in pressure required to force the lower plug through the constricted bore 26, thereby indicating that the liquid charge 85 has begun to enter the well bore, the decline in pressure is generally of the same order of magnitude (1000-1800 pounds per square inch) as the differential pressure required to drive in plug through the constricted bore. The position of the upper plug in the tubing depends upon the volume of the charge and that of the bore of the tubing. Large charges cannot always be introduced into the tubing before the first plug is driven into the well hole. The usual charge is generally smaller than the volume of the tubing so that both plugs may be present in the tubing at one time as shown in Fig. 4.

As the charge 85 enters the well bore, the top plug continues to descend under the force of the driving fluid column 84 until the upper plug comes to rest against funnel section 27, as at 83 in Fig. 6, preventing the pressuring fluid 84 from entering the well under the pressure being applied. As in the case of the first plug, a large differential pressure is required to force the second plug through the constricted bore of the element 24 so that an abrupt and greatly increased gauge reading signals the arrival of the resilient plug at the constrictional element and, hence, the complete expulsion of the liquid charge into the well. The charge thus deposited in the well is indicated at 89. The depth attained by it in the well hole varies mainly with the volume of the charge and that of the hole, the porosity of the surrounding earth, and the rock pressure.

Similar procedure is followed in those instances

where the liquid or fluid charge introduced into the well is to be confined below a predetermined elevation as by including in combination with the tubing string a packer. This procedure may be followed in the well already described using such an apparatus as illustrated in Fig. 7, in which the constrictional element 44 and packer 42 are attached to the end of tubing string 8 of the well of Fig. 1, thereby forming a complete assembly using a short length of tubing 45 to join the packer with the constrictional element 44. The assembly is lowered into the well bore 1 as before until the packer 42 is at the top 90 of the zone 30 at which a fluid charge is to be spotted and then the packer 5 is set against the wall of the well hole, as shown, so as to prevent liquid introduced into the well from rising in the bore above the zone, the hole below the bottom of the zone being bridged as described. The delivery of a charge of treating agent into the well is accomplished in the same manner as that already described with the apparatus of Figs. 1, 2, 4, 5, and 6. This procedure and apparatus provided enables a charge of a fluid agent to be directed without significant loss of 10 volume through the tubing into a specific zone 25 30 of the well hole lying between the upper elevation 90, just below the packer 42, and the lower elevation adjacent to the top 32 of the bridge 31. After the injection into the zone of a fluid agent, 20 the packer may be released and the apparatus withdrawn from the well, as desired. If the fluid agent used prevents the withdrawal of the constrictional element, as when a cementing agent is used, the tail pipe portion 45 may be made of 25 30 35 drillable metal so that it may be drilled up after disconnecting the packer from it.

If desired, a modified form of constrictional element, as shown at 47 in Fig. 8, may be placed between the end of the tubing string 8 and a packer 53 using a short length of tubing 54 to join them, thereby obtaining all the advantages of the arrangement of Fig. 7 and the further advantage of a back-pressure valve which may be closed with the last resilient plug, thereby preventing the charge or other fluid returning once the plug is seated against the valve. In using this form of the apparatus, the procedure is generally the same as that already described, the assembled apparatus being lowered into the well so that the packer 53 may be set at the top 90 of the zone 30 to be treated, the tail pipe 59 extending into the well hole below the packer. The head of the well may be equipped as in Fig. 1 and the apparatus, referring to Fig. 8, is attached to the tubing 8 in place of that shown in Figs. 2-7, inclusive, thereby providing a continuous passage from the lock chamber 14 into the well hole 1 below the packer 53 when valve 9 is open.

Prior to introducing a fluid agent into the well hole, with the apparatus arranged as in Fig. 8, a resilient plug is inserted in the lock chamber, as already described in connection with Fig. 1, and then the fluid agent is introduced driving the plug ahead of it down the tubing. When all the charge 60 has been introduced, a second resilient plug is inserted and then a pressuring fluid, such as oil or water, is introduced so as to drive the charge into the well hole. When the first plug arrives at the bore constricting element 47 an abrupt increase 65 in pressure of from about 1000 to 1800 pounds per square inch is observed on gauge 20. Pumping or the application of pressure to the driving fluid is continued so as to drive the first plug through the constriction 47, tube 54, packer 53, and tail pipe 59 into the bore 1 below the packer. After 70 75

the first plug is thus driven out of the tail pipe, it drops into the well hole, as indicated by numeral 92, and the pressure reading declines abruptly indicating this result. After the first plug is thus driven into the well hole, introduction of pressuring fluid is continued, thereby delivering the charge of fluid agent into the well. The charge fills the space between the bottom 93 of the packer and the top 32 of the bridging plug 31 and if the volume of the charge exceeds that of the space the balance may be pumped into the zone 30. The pressure indicated on the gauge 28 is observed during the introduction of pressuring fluid and when an abrupt rise of as much as 1000 to 1800 pounds per square inch, more or less occurs, it indicates that the second plug has arrived at the constriction 47 and the charge is fully expelled from the tubing. Sufficient pressuring fluid is then introduced to just drive the second plug through the constriction 47 but not into the well hole, thus allowing the second plug to remain in the tubular section 54 below the valve seat 49 as indicated at 93. In this position, the upper lip 94 of the plug abuts against the conical shoulder 49 which prevents the plug from being pushed upward into the constricted bore of 47 by fluid pressure acting on the lower end of the plug. Thereby, the plug acts as a back-pressure valve-closure for the tubing so that maintenance of pressure on the pressuring fluid in the tubing is unnecessary after the charge is expelled. After the charge has done its work, the packer may be released and the apparatus withdrawn.

If the fluid charge delivered into the well hole through the apparatus is a cement, the release of the packer is not always possible. However, since the cement, if used, is completely expelled from the tubing string to a point below the upper plug when in the position 93, it is customary to disconnect the nipple 54 from element 57, pull the tubing out of the well, and then drill out the packer.

The apparatus of Fig. 9 is especially adapted for spotting cementitious fluids, particularly of the type which by chemical change, such as polymerization or condensation, become resinous solids. Liquid compositions of this type are now well known and their use exemplified in the aforementioned U. S. Patent 2,274,297. A typical application of the apparatus is its use in spotting a sealing agent behind perforated casing as depicted in Figs. 10 to 14, inclusive, wherein a specific zone 72, as for example one containing water, behind the cemented casing 3 is to be sealed by injecting into the zone a charge of a resin-forming liquid sealing agent through the perforations 71. This is accomplished by equipping the head of the well with the apparatus of Fig. 1 and securing the upper end 62 of the assembly of Fig. 9 to the lower end of the tubing 8, the length of which has been chosen so that the discharge end 95 of the lower constrictional element 69 will be adjacent the lowermost perforations when lowered into the casing of the well, the hole below the perforations being bridged temporarily as previously described with the bridge 70. After lowering the tubing and appended apparatus, the casing head 5 is made fast to the casing 3 and the tubing 8 to the casing head. It is advantageous usually to wash the well clean of drilling mud, if any be present, by circulating water down the casing and up the tubing, as by introducing water through valved connection 6, valves 9 and 12 being open, 1, 13, 17, and 19 being closed, circulation of water 75 the sealing fluid.

is continued until the discharge from valve 12 runs clear, valved connection 6 then being closed. Plug 15 is removed and a first resilient plug inserted in the lock chamber 14 thereafter plug 15 is replaced and valve 12 closed. Valve 17 is opened and a measured quantity of sealing fluid, such as a partially condensed phenol-aldehyde mixture containing a catalyst for inducing further condensation to a hard resin when in the well formations, is introduced through the valved connection 19. Accurate measurement of the volume of sealing fluid used is best accomplished by means of a calibrated tank. After introducing a suitable amount, such as 5 to 100 gallons, more or less, depending on the amount of sealing to be done, valve 9 is closed, 12 opened, plug 15 removed, and a second resilient plug inserted in the lock chamber 14. The plug 15 is replaced, valve 12 closed, valves 6 and 9 opened, and a pressuring fluid, preferably one of lower specific gravity than the sealing fluid, such as water, is introduced through the valved connection 19, thereby driving the two resilient plugs and charge of sealing fluid subtended by them down the tubing string. Only a moderate pressure is usually required for this operation. During the descent of the plugs and charge fluid displaced thereby from the well is allowed to escape from the casing through valve 6.

30 The arrival of the first plug at the upper constrictional element 63, as shown in Fig. 10 at 96, is signalled by an abrupt rise in pumping pressure on the pressuring fluid, as indicated on gauge 20, and the charge of sealing fluid then 35 comprises the fluid column 97 occupying the space below the second plug 98, the pressuring fluid 99 being shown above it. The pumping pressure is allowed to increase to the extent necessary to drive the lower resilient plug into the tubular section 66, as shown at 100 in Fig. 40 11, whereupon the pumping pressure abruptly decreases until the downward travel of the lower plug is again arrested by the lower constrictional element 69. The pressure signals thus produced 45 by the passage of the first plug through the upper constrictional element 63 and its abutting against the lower constrictional element 69 signify that the sealing fluid column 97 is at the bottom of the tubing in position to begin its 50 entry into the casing above the bridge 70.

The pumping pressure is then increased so as to expell the lower plug into the casing and the fluid charge, the complete expulsion of which is signalled by an abrupt rise followed by an abrupt 55 fall of the pumping pressure as the second plug is driven into the tubular section 66 as shown in Fig. 12. The pressure then abruptly rises again as the upper plug abuts the lower constrictional element 69. The pressure is not permitted to increase sufficiently to expell the second plug; instead this plug is allowed to remain 60 in the tubular section 66 to act as a back-pressure valve-closure preventing return of sealing fluid from the casing into the tubing string.

65 During the delivery of the sealing fluid into the casing, a corresponding volume of displaced fluid is usually discharged from the casing head through valved connection 6. It is advantageous to measure this volume as it serves as a means of approximately computing how much of the sealing agent has entered the formation through the perforations 71, as the volume of fluid discharged from the casing corresponds to the volume of the space occupied in the casing by 70 the sealing fluid.

In the case illustrated, the sealing fluid is shown to have risen in the casing outside the tubing to a level 100 well above the perforations. After discharging the sealing fluid into the casing, the tubing is elevated so that the discharge end 95 is raised above the top 101 of the column of sealing fluid in the casing, as in Fig. 13. The casing head valve 6 is then closed and pumping of pressuring fluid through valved connection 19 is then continued so as to expell the last resilient plug from the tubular section 66, the expulsion of this plug being signalled by an abrupt decrease in pumping pressure. After expelling the last plug which drops into the well hole, as shown in Fig. 14, pressuring fluid is introduced into the casing, preferably through the tubing 8 so as to displace the sealing fluid from the casing and lowering the level of sealing fluid therein as indicated at 102, the displaced fluid entering the zone behind the perforations, thereby impregnating the formation with sealing fluid as indicated by the shaded section 103. Sufficient pressure is maintained on the pressuring fluid to keep the sealing fluid in place until set, the pressure is then released and the tubing and appended constrictional elements withdrawn from the well. Any sealing fluid set up in the casing is removed as by drilling.

It will be understood that while the use of the apparatus and method of the invention has been described and illustrated largely as being applied to different zones of the same well, this is not to be construed as limiting the invention either to such applications or to wells having the zones illustrated, as the invention may be used in various types of wells whether cased or not and irrespective of the number and kinds of zones traversed by the well bore.

Furthermore, although in the preferred embodiment of the invention its use is illustrated in spotting a sealing fluid, it will be understood that other treating fluids, such as acidizing solutions, e. g. 5-25 per cent hydrochloric acid solutions, may be spotted similarly.

It will be apparent, also, that the apparatus of Fig. 9 may be used in combination with a packer or drillable retainer, such as a conventional cement retainer, for example, a model "K" cement retainer manufactured by Baker Oil Tools, Inc., the lower end 95 being connected preferably to the top of the retainer. The bore through the mandrel of the retainer should be substantially the same as that of the tubing string, so that fluids and plugs driven through the tubing string and constricted bores 63 and 69 have a continuous unobstructed passage through the retainer. With such combination, it is advantageous to provide circulation jars on the tubing string above the retainer although the apparatus may be used without them.

The apparatus of Fig. 9 is also similarly adapted for use with a conventional retractable retainer or packer instead of drillable retainers or packers. The apparatus is assembled in the tubing string either above or below the packer or retainer. If assembled above the retainer, it is advantageous to provide a sufficient length of tail pipe below the retainer to prevent cementitious fluids delivered through the apparatus into the well from rising upward in the bore to the retainer, thereby getting into the slips and other working parts of the retainer. With such an arrangement, the last resilient plug introduced behind the fluid material being spotted serves as a back-pressure valve-closure by lodging in the

tubular section 66, the upper end of the plug abutting the valve seat portion of the constricted bore element 63. After the fluid is spotted, the last plug may then be driven into the well by applying sufficient fluid pressure through the tubing and then the retainer or packer is set. After setting the packer, fluid pressure is applied through the tubing, the amount of fluid so used being measured at the head of the well so that the desired amount of displacement of the introduced fluid into the well formations is thereby ascertained and controlled. If the fluid material so introduced is a cement, e. g. synthetic resin-forming liquid, the pressure applied to produce the displacement from the apparatus into the well is maintained until the material has set. Then the retainer is released and the apparatus withdrawn from the well.

We claim:

20. An apparatus for spotting a fluid material at a selected zone in a well comprising the combination of a tubing string having a substantially uniform unobstructed bore from end to end; an upper tubular member having an unobstructed cylindrical bore 25 to 70 per cent less in cross-sectional area than that of the tubing string and a length at least 3 times its diameter, the upper end of the said upper tubular member being secured to the lower end of the tubing string; a tubular section on the lower end of the upper tubular member said tubular section having substantially the same bore as the tubing string; a lower tubular member on the lower end of the tubular section, said lower tubular member having an unobstructed cylindrical bore 25 to 70 per cent less in cross-sectional area than that of the tubular section, the combination being adapted to be lowered into the well so that the last mentioned tubular member is opposite the selected zone.
25. An apparatus for spotting a fluid material at a selected zone in a well comprising the combination of a tubing string having a substantially uniform unobstructed bore from end to end; a first tubular member having an unobstructed cylindrical bore 25 to 70 per cent less in cross-sectional area than that of the tubing string, the upper end of said first tubular member being secured to the lower end of the tubing string; a tubular section on the lower end of the first tubular member said tubular section having substantially the same bore as the tubing string; a second tubular member on the lower end of the tubular section said second tubular member having an unobstructed cylindrical bore 25 to 70 per cent less in cross-sectional area than that of the tubular section, the lower end of the bore of the first tubular member having a recess forming a valve seat whereby a resilient piston-like plug lodged in the tubular section forms a closure therefor when urged upwardly against the seat, the combination being adapted to be lowered into the well so that the second tubular member is opposite the selected zone.
30. An apparatus for spotting a fluid material in a well adapted for use on the lower end of a string of tubing having an unobstructed bore from end to end comprising a pair of short tubular members, each having an unobstructed relatively small bore compared to that of the tubing string, and a short section of tubing joining the said tubular members and having the same bore as the tubing string, said tubular members and tubular section being in axial alignment and forming a continuous passage for fluid and for a re-

silient compressible tubing plug making a sliding sealing fit with the bore of the tubing string.

4. An apparatus for spotting a fluid in a well for use on the lower end of a string of well tubing in combination with a resilient compressible tubing plug driven by a driving fluid through the bore of the tubing behind the fluid being spotted, the plug producing a pressure increase on being driven into the apparatus signalling completion of spotting and there acting as a back-pressure valve preventing the return to the tubing of the spotted fluid, comprising a tubular assembly having an upper, a middle and a lower section all connected in tandem forming a continuous passage from end to end, the upper end of the tubular assembly having means for attachment to the lower end of the string of well tubing, the cross-sectional area of the bore of the said upper and lower sections being between about 25 and 70 per cent of that of the said middle section, the cross-sectional area of the bore of the said middle section being substantially the same as that of the tubing string, said middle section having a length sufficient to accommodate in its bore the resilient compressible plug driven thereinto through the upper section by the driving fluid, the lower end of the said upper section having a shoulder adapted to engage the upper end of the resilient plug to close the passage when urged upwardly in the said middle section.

5. An apparatus for spotting a fluid material in a well for use on the lower end of a string of tubing suspended in the well comprising an upper tubular member having a constricted axial bore therethrough, means at the upper end of said upper tubular member for attachment to the lower

end of the tubing string, said upper tubular member having an annular recess in the lower end; a coniform projection in the annular recess; a lower tubular member having an axial bore therethrough; an intermediate tubular member connecting the upper and lower tubular members said intermediate tubular member having a cross-section substantially the same as that of the string of tubing, the cross-section of the bore of said upper and lower tubular members being about 25 to 70 per cent of that of said intermediate tubular member, whereby a resilient compressible plug making a sliding sealing fit in the bore of the string of tubing requires the application of a substantial additional driving pressure to force the plug from the tubing through the said tubular members as the fluid material is delivered to the well through the tubing string.
